(57) **CLAIM**

The ornamental design for an computer screen with animated graphical user interface, as shown and described.

DESCRIPTION

1. Animated graphical user interface
2. Animated graphical user interface
1.1 : Front view of a first image of a computer screen with animated graphical user interface;
1.2 : Second image thereof;
2.1 : Front view of a first image of a computer screen with animated graphical user interface showing a second embodiment; and
2.2 : Second image thereof.
The appearance of the animated graphical user interface transitions sequentially between reproductions 1.1. and 1.2 in embodiment 1, and between reproductions 2.1 and 2.2 in embodiment 2. The process and period in which one image transitions to another forms no part of the claimed design. The broken lines showing a computer screen in reproductions 1.1-2.2 illustrate portions of the article and form no part of the claimed design.
Animated graphical user interface.
